UNITED STATES PATENT OFFICE.

HENRY M. HUXLEY, OF EVANSTON, ILLINOIS, ASSIGNEE TO ECONOMY FUSE & MANUFACTURING COMPANY, OF CHICAGO, ILLINOIS, A CORPORATION OF NEW YORK.

RENEWABLE CARTRIDGE-FUSE.

1,129,395.

Specification of Letters Patent. Patented Feb. 23, 1915.

Application filed March 20, 1914. Serial No. 825,964.

To all whom it may concern:

Be it known that I, HENRY M. HUXLEY, a citizen of the United States, residing at Evanston, in the county of Cook and State 5 of Illinois, have invented certain new and useful Improvements in Renewable Cartridge-Fuses, of which the following is a specification.

My invention relates to renewable cartridge fuses, and is particularly, although 10 not exclusively, adapted for use in connection with inclosed fuses of the ferrule type.

In the co-pending application of Alfred L. Eustice, Serial No. 825,957, filed March 15 20, 1914, a renewable cartridge fuse is described in which each end of the fusible link is clamped between a clamping arm attached to the cap member and a clamping arm formed integral with an end washer of the 20 fuse, these two clamping arms being drawn toward each other, in order to tightly clamp the end of this link in position, by means of a suitable screw which passes through apertures in the end cap and shell of the fuse, 25 thereby serving at the same time to hold the end cap in position.

The disadvantage of the construction which I have just described resides in the fact that the ends of the fusible link which 30 are bent over the end washers are not brought into tight contact with the insides of the cap members, these cap members being provided with apertures through which portions of the link may be inspected.

35 In case of a violent blowing of the fuse under short circuit, inflammable gases are liable to escape through these inspection apertures.

It is the object of my invention to provide 40 means by which the ends of the fusible link are tightly clamped between the clamping arms of the caps and end washers, while at the same time the bent-over ends of the fuse link are tightly clamped against the end 45 caps. These and other advantages of my invention will be more readily understood by reference to the accompanying drawings, in which:

Figure 1 is a side elevation of my im- 50 proved cartridge fuse. Fig. 2 is a longitudinal section taken on the line 2—2 of Fig. 1. Fig. 3 is a transverse section taken on the line 3—3 of Fig. 2. Fig. 4 is a fragmentary enlarged longitudinal section showing the construction used at the ends of the

fuse, and Fig. 5 is a perspective of one of the end washers.

My inclosed cartridge fuse is provided with the tubular shell 10, of fiber or other suitable insulating material. At each end 60 of the shell 10 is provided an end cap 11, which fits snugly over the end of the shell. Each of the end caps 11 has securely fastened thereto a clamping arm 12, which has a threaded aperture 13. An end washer 14 65 is located at each end of the shell 10 and is provided with a clamping arm 15, which is parallel with the clamping arm 12. The clamping arm 15 is preferably provided with a slot 16 in its end. 70

The fusible link 17 is preferably flat and extends through the tubular shell 10. At each end, the link 17 passes between the clamping arms 12 and 15, the apertures 18, near each end of this link, registering with 7 the threaded apertures 13 in the clamping arms 12. The screw 19 passes through an aperture in each of the end caps 11 and through a corresponding aperture in the shell 10. Each of these screws is provided 80 with a threaded end 20, adapted to engage the threaded aperture 13 of the clamping arm 12. The screw 19 also has a beveled shoulder 21, which is adapted to engage the end of the recess 16 in the clamping arm 15. 85 Each end of the fusible link 17, after passing between the clamping arms 12 and 15, is bent over the body portion of the end washer 14 and may be inspected through an aperture 21^a in the end cap 11. As the screw 90 19 is screwed home, the clamping arm 16 of the washer 14 is forced toward the clamping arm 12 by means of the beveled shoulder 21, while at the same time this beveled shoulder also serves to move the entire 95 washer toward the end cap, thereby simultaneously performing the two functions of clamping the link 17 between the clamping arms 12 and 15 and clamping the over-turned end of this link between the washer 100 14 and the end cap. This clamping action is well illustrated by Figs. 2 and 4. In Fig. 4 the screw 19 is shown in position before it has been screwed home, so that in this position the over-turned end of the link 17 105 loosely occupies the space between the washer 14 and the inner surface of the cap member 11. After the screw 19 has been screwed home, the washer 14 is bodily moved in an outward direction and securely clamps 110

the over-turned end of the link 17 in the manner indicated in Fig. 2.

In order to disassemble the fuse of my invention, it is only necessary to withdraw the screws 19, after which the end caps, and then the end washers may be readily removed. In assembling the fuse, the end washers are first placed in position, the fusible link 17 is then inserted within the shell 10, and the ends of this fuse link are bent over the end washers. The end caps are then applied and the screws 19 finally inserted and screwed home, when the clamping action above mentioned takes place.

15 In order to cause the gradual escape to the atmosphere of the gases which are generated on blowing of the fuse, I preferably employ, near each end of the shell 10, a spiral venting passage 23, which causes the 20 gases to become materially cooled before reaching the atmosphere.

Although my invention is particularly adapted for cartridge fuses of the ferrule type, it may also be used for knife-blade fuses, by extending the clamping arms 12 to 25 form the blades 22, as indicated in dotted lines in Figs. 1, 2 and 4.

It will be apparent to those skilled in the art that many changes could be made in the 30 detailed construction of the various parts which I have described without departing from the spirit or scope of my invention.

What I claim is:

1. In a cartridge fuse, the combination of 35 a shell, a cap fitting over each end of said shell, a clamping member between said cap and the end of said shell, said cap and said shell having registering apertures there-through, a fusible link extending through 40 said shell and having a bent-over end between said clamping member and said cap, and wedging means extending through the apertures of said cap and shell and engaging said clamping member, whereby said cap 45 is secured to said shell and said clamping member may be forced toward said cap, whereby the bent-over end of said link will be tightly secured between said cap and said clamping member, substantially as described.

50 2. In a cartridge fuse, the combination of a shell, a cap fitting over each end of said shell, an end washer between said cap and the end of said shell, said end washer having an arm extending inwardly into said shell, said cap and said shell having registering apertures through their sides, a fusible link extending through said shell and having a bent-over end between said washer and said cap, and a screw passing through 55 the apertures of said cap and shell and having wedging engagement with the arm of said end washer, whereby said cap is secured to said shell and said washer may be forced toward said cap, thereby tightly securing 60 the bent-over end of said link between said

cap and said end washer, substantially as described.

3. In a cartridge fuse, the combination of a shell, a cap fitting over each end of said shell, said cap having a clamping arm 70 extending into said shell, a link extending through said shell, and means for clamping said link against said clamping arm and against the inner surface of said cap, substantially as described.

75 4. In a cartridge fuse, the combination of a shell, a cap fitting over each end of said shell, said cap having a clamping arm extending inwardly into said shell, a clamping member between said cap and the end 80 of said shell, said clamping member having a clamping arm extending parallel with the clamping arm of said cap, a fusible link extending through said shell and between the clamping arms of said clamping member 85 and said cap having a bent-over end between said clamping member and said cap, and common means for moving said clamping member toward said cap and its clamping arm toward the clamping arm of said cap, 90 whereby said link will be tightly secured between said clamping arms and between said clamping member and said cap, substantially as described.

95 5. In a cartridge fuse, the combination of a shell, a cap fitting over each end of said shell, said cap having a clamping arm extending inwardly into said shell, a clamping member between said cap and the end of said shell, said clamping member having a 100 clamping arm extending parallel with the clamping arm of said cap, a fusible link extending through said shell and between the clamping arms of said clamping member and said cap having a bent-over end between 105 said clamping member and said cap, and common means for securing said cap to said shell and for simultaneously moving the said clamping member toward said cap and the clamping arm of said clamping member 110 toward the clamping arm of said cap, whereby said fuse is tightly secured between said clamping arm and the bent-over end of said link is tightly secured between said clamping member and said cap, substantially as 115 described.

6. In a cartridge fuse, the combination of a shell, a cap fitting over each end of said shell, said shell and said cap having registering apertures through their sides, a 120 clamping arm secured to said cap and extending inwardly into said shell, said arm having a threaded aperture therein, an end washer between the end of said shell and said cap, said washer having a clamping arm extending parallel with the clamping arm of said cap, a fuse link extending through said shell and between said clamping arms and having a bent-over end between 125 said end washer and said cap, and a 130

screw extending through the apertures of said cap and said shell and having engagement with the threaded aperture of the clamping arm of said cap, said screw having a beveled shoulder engaging the clamping arm of said end washer, whereby, on rotation of said screw, said end washer is

forced toward the clamping arm of said cap, thereby securely holding said link in position, substantially as described.

HENRY M. HUXLEY.
